DAYTON B. HOLCOMB, OF PASADENA, CALIFORNIA

SURGICAL GARMENT

Application filed August 28, 1928. Serial No. 302,585.

My invention relates to surgical garments, of the kind referred to as corsets or girdles.

It is a fact, both from a physical and a radiological examination, that in all cases of 5 visceral ptosis or prolapsus, the spinal two-arch gravity point from the tenth dorsal vertebra downward to the eleventh, twelfth dorsal, first and even the second lumbar vertebrae is lowered. The thoracic cage drops very materially, which, in turn, narrows greatly the anterior posterior thoracic measurements, relaxing the diaphragm, and the abdominal content is pushed downward to a state of prolapsus. Anterior to the spine at the cross- 10 ing point of the tenth dorsal vertebra or spinal arches lies the solar plexus or the abdominal brain of the sympathetic nervous system, which controls all the chemical action of the digestion and of the abdominal organs. 15 In all body movement in an erect position, if this gravity point is lowered, there is always more or less diminution of the creative natural impulses upon this abdominal brain, and the body economy is positively so interfered with that the most vital metabolism, influencing the ferments, results. 20

With the foregoing clearly in mind, it is an important object of my invention that the garment be so constructed as to relieve the 25 herein-stated prolapsed condition and perform its intended functions in conformity with the anatomical lines of the body, and without producing undue pressure over the abdomen.

30 A further object of my invention is to provide a garment that will properly adapt itself to the iliums and allow for free natural movements when the wearer is walking or sitting and which will conform to the anatomical lines of the body and afford comfort to the patient, and leave the organs free, mobile and nearer their normal position than has been possible heretofore where use is made 35 of garments that are dependent entirely upon induced pressure created by well known mechanical means and which have been found detrimental to the female pelvic organs.

In the accompanying drawings,

40 Figure 1 is a front view of the garment;

Figure 2 is a view in side elevation showing the garment applied; and

Figure 3 is a section on line 3—3 of Figure 1.

The corset 5 herein illustrated, aside from the details of construction forming my invention, may be of any approved form. In the present instance, the corset is provided at suitable intervals with stays 6, and at the front the corset carries a lacing 7 trained through the eyelets 8, so that the same may be made to adjust itself to the body to suit the requirements.

To the respective sides of the open front of the corset and continued into the material of which the garment is formed are panels 9—9 which are adapted to fit over the anterior portions of the iliums far enough posterior thereof that the seam A attaches to the back part of the garment, as shown. In this manner, the construction allows for the natural swinging anterior and posterior movements, respectively, of the femur in walking. The superior margins B of said panels occupy positions above the crests of the iliums, including the anterior superior spines thereof. The anterior seams C find their juncture at the upper ends of the seams A and from these points the same extend anteriorly over the crest and anterior spine, then inferiorly or downward along irregular lines which are adapted to conform to the curved anterior line and the ligament attachments from the anterior superior spine to the pubis. The said seams C terminate at the bottom of the garment, and at points between the seams A and C each panel is formed with a lower portion which is flared or widened forming a fullness to conform to the contour of the upper thigh lateral and to extend over the femurs.

The seam C, after crossing in front of and above the superior spines, is cut posteriorly so as to create a pinch which centers at a point over Poupart's ligament, where the ligament of Gimbernot attaches thereto, so that a pull is exerted on the attached front wall portions of the garment on lines extending diagonally upward from the pubis and substantially in line with the lay of Poupart's

ligament, such direction of pull at one side of the front of a body being indicated by the line $x-y$ on Figure 2 of the drawing. The front of the corset is designed to follow the pubic lines, whereby to press inwardly and upwardly to create an uplift to the prolapsed or ptosed viscera, and which also serves or functions to hold the prolapsed colon.

10 It is understood that the normal lines of the abdominal wall are supposed to be nearly flat from the lateral body lines across and from the costal arch superiorly to the pubic line inferiorly. That the bulging of the abdomen, and especially below the umbilicus or navel, is unnatural to the human body, generally speaking, and that this bulging is due to visceral prolapsus, which may be known as splanchnoptosis, or ptosis, and it follows from radiological examinations that the necessity of uplift depends upon the reconstruction of the normal body gravity line and the enforced uplift to conform to the natural flat anterior line of the abdomen. I am able to overcome the heretofore existing defects in surgical garments of the kind stated by a corrective scheme which is free from the theory of externally created pressures that are applied by lacing or straps and buckles. The functional attainments are reached through my garment without any detriment to the female pelvic organs such as is caused by inward pressure only. When my garment is worn by a patient, I find that when the patient is in a standing position, the fingers when applied within the yaginum reveal the organs free and mobile and nearer their normal position, whereas, and when excessive pressure is resorted to, the organs are found prolapsed, which is convincing that, and by virtue of my garment, the abdominal content is lifted from the pelvic organs. I am able to overcome the pre-existing faults and through means that will not result in any diminution of the creative natural impulses upon the abdominal brain and the body economy that would interfere with the vital metabolism that influences the fermentations.

50 It will thus be seen that the faults existing in surgical corsets and garments of this character are corrected by this invention which is accomplished by forming the surgical corset with the peculiarly constructed lateral panels 9 each of which has fullness at its upper front portion as shown at 9^a and also at 9^b at its lower front portion while between the two there is a straight unfulled portion 9^c which produces a pinching effect which centers at a point over Poupart's ligaments where the ligament of Gimbernot attaches. The front of the corset is so cut that it follows the pubic lines and exerts an inward and upward pressure thereby uplifting the prolapsed or ptosed viscera.

Hence it will be obvious that these panels 9 constitute the gist of applicant's invention and their peculiar formation in connection with the front portion of the garment produces the desired effect, that is to lift and hold the organs so as to provide for healing thereof.

I claim as my invention:

1. A surgical garment having oppositely arranged frontal means to cause the abdominal content to be lifted off from the pelvic organs, said means each comprising an intermediate portion adapted to fit substantially taut over an ilium and in a manner to exert a pull on the adjacent front wall portion of the garment in a direction approximating that of the lay of Poupart's ligament, a lower portion fulled to conform to the contour of the upper thigh lateral and to extend over the femurs, and an upper portion fulled at a point above Poupart's ligament where the ligament of Gimbernot attaches thereto, the said means being secured to adjacent front wall portions of the material of the garment by anterior-irregular-seam lines, which cross in front of and above the superior spines.

2. A surgical garment for correcting visceral prolapsus comprising a corset having lateral parts respectively occupying positions at the sides of the front of the garment, said parts each having an intermediate portion to fit substantially taut over an ilium and in a direction diagonally upward from the pubis and passing through the point of juncture of Poupart's ligament with the ligament of Gimbernot, a portion flared and widened below the intermediate portion to conform to the contour of the upper thigh laterals and the femurs, and a portion fulled immediately above the said intermediate portion to engage over the approximate line of the crest of the iliums, the front of the garment being formed to merge into and co-act with said intermediate portions to follow the pubic lines of the body so that the garment presses inwardly and upwardly, creating an uplift to the prolapsed or ptosed viscera.

3. A surgical garment for use in the treatment of visceral ptosis, having lateral panels, said panels being attached by seams respectively to the back and front portions of the garment and provided with superior, inferior fulled portions occupying positions above the crests of the iliums including the anterior superior spines thereof, the anterior seams of the panels beginning at the back of the garment and extending to a point anteriorly over the crest and anterior spine; thence inferiorly and irregularly to conform to the curved anterior line and the ligament attachments from the anterior superior spine to the pubis, the said panels extending to the bottom of the garment and being fulled to conform to the contour of the upper thigh lateral and over the femurs, the said anterior seams of the

5 panels after crossing in front of and above the superior spines, being formed with intermediate portions to produce a pinching effect which centers at a point over Poupart's ligaments where the ligament of Gimbernot attaches, the front of the garment being formed between the panels to follow the pubic lines to thereby press inwardly and upwardly against the prolapsed or ptosed viscera to
10 restore the normal body gravity line and cause the abdomen to assume a flat anterior line, the front of the garment being open along a vertical line and provided with an adjusting lace.
